CLAIM

The ornamental design for a draining-board for dishes and cutlery, as shown and described.

DESCRIPTION

FIG. 1 is a top perspective view of a draining board for dishes and cutlery showing my new design;

FIG. 2 is a top plan view thereof;

FIG. 3 is a bottom plan view thereof;

FIG. 4 is a side elevational view thereof, the opposite side being a mirror image; and

FIG. 5 is an end elevational view thereof, the opposite end being a mirror image.
